UNITED STATES PATENT OFFICE

HENRY W. GROM, OF NEWARK, NEW JERSEY, ASSIGNOR TO CONTINENTAL OPTICAL
FRAME COMPANY, OF NEWARK, NEW JERSEY, A CORPORATION OF NEW JERSEY

DESIGN FOR A COVER PLATE FOR SPECTACLE-FRAME END PIECE

Application filed January 29, 1930. Serial No. 34,334. Term of patent 14 years.

To all whom it may concern:

Be it known that I, HENRY W. GROM, a citizen of the United States of America, residing at Newark, in the county of Essex and State of New Jersey, have invented a new, original, and ornamental Design for Cover Plate for Spectacle-Frame End Piece, of which the following is a specification, reference being had to the accompanying drawing, forming a part thereof.

The figure is a front elevation of a cover plate for spectacle frame end piece, showing my new design, the same being of no appreciable thickness, and the broken lines merely disclosing its appearance when in use.

I claim:

The ornamental design for a cover plate for spectacle frame end piece, as shown and described.

HENRY W. GROM.
